FLUID FUEL BURNER CONTROL SYSTEM

Joseph P. Ashcraft, Dallas, Tex., assignor to Minneapolis-Honeywell Regulator Company, Minneapolis, Minn., a corporation of Delaware

Application June 5, 1940, Serial No. 338,938

7 Claims. (Cl. 158—115)

This invention relates to a fluid fuel burner control system, and more particularly to one employing a pilot burner, wherein means is provided to shut down the main burner upon failure of the pilot flame.

In fluid fuel burner control systems employing a pilot burner, it has been proposed to place the hot junction of a thermocouple in the pilot flame, and to provide means responsive to a drop in the thermocouple E. M. F. such as occurs upon flame failure, to shut down the burner. Such systems which have been built in the past have been slow to respond to failure of the pilot flame, because of the relatively long time necessary for the hot thermocouple junction to cool down enough to produce the required drop in E. M. F. The thermocouple response has been particularly slow in those cases wherein the hot junction was exposed to radiation from the main burner flame, and pilot failure has occurred while the burner was in operation. Radiation from hot furnace walls has likewise sometimes delayed the thermocouple response when the pilot failed immediately after the burner was shut down. Radiation from the main burner flame, and from hot furnace walls, are particularly apt to be troublesome in large burners employing a forced draft, which usually operate at a higher temperature than natural draft burners. Furthermore, forced draft burners are especially liable to have their pilot burner extinguished, because of the rapid air movements near the burner.

Another difficulty with the devices proposed in the past has been that the copper conductors leading to the thermocouple have tended to oxidize in the intense heat to which they are exposed.

An object of the present invention is to construct a pilot burner and thermocouple arrangement, wherein means are provided to accelerate the cooling of the hot junction of the thermocouple upon extinguishment of the flame.

Another object of the invention is to construct a pilot burner and thermocouple arrangement wherein the gas flowing through the burner is utilized to increase the difference in temperature of the hot and cold junctions during normal flame conditions, and to reduce the difference in temperature when the flame becomes extinguished.

A further object of the invention is to construct a pilot burner and thermocouple device wherein the thermocouple is so situated relative to the gas burner that the gas flowing toward the burner conducts heat away from the cold junction of the thermocouple, and the gas flowing from the burner after flame failure conducts heat away from the hot junction.

A still further object of the present invention is to provide a pilot burner and thermocouple device wherein the electrical leads to the thermo-

couple are protected against the heat of the burner. It is also an object of this invention to utilize the gases flowing to the pilot burner to cool the thermocouple leads.

5 Other objects of the present invention will be apparent from a consideration of the specification, claims, and drawing, of which:

Figure 1 is a diagrammatic sketch of a fluid fuel burner control system embodying my invention.

Figure 2 is an enlarged view, partly in cross section, showing my invention as applied to a commercial type of pilot burner.

Figure 3 is an exploded view of the packing washers used in carrying the thermocouple leads of my invention through the wall of the pilot burner fuel supply conduit, in their assembled relation, and

Figure 4 is a vertical sectional view of the thermocouple on a considerably larger scale than in Figure 2.

In the drawing the wall of a gas burning furnace is indicated at 10. A main burner 11 is mounted adjacent an opening in this wall and is connected by pipe 12 with a motor driven mixer and blower 13. Gas is supplied to the mixer through the pipe 14 and air through another pipe 15. An electrically operated valve 16 of any suitable type is connected in the pipe 14. A smaller pipe 17, connected to the pipe 14 on the inlet side of the valve 16, conveys fuel to a pilot burner generally indicated at 18.

The energization of the motor of the mixer and blower 13 is controlled by a thermostat 20 which is located in the room or space being heated by the furnace. This thermostat comprises a bimetallic element 21 to which is secured a contact arm 22 for cooperation with the stationary contact 23. A magnet 24 is located adjacent the contact arm 22 and serves to impart a snap action thereto.

A thermocouple indicated schematically at 25 located within the pilot burner 18 is electrically connected to a solenoid 26 of a safety switch 27 which may be of any suitable type, such as that disclosed in Patent No. 2,165,801, issued to Carl G. Kronmiller on July 11, 1939. The switch 27 comprises in addition to the solenoid 26 a switch arm 28 and a stationary contact 29. Under normal flame conditions, solenoid 26 is energized sufficiently by thermocouple 25 so that it will hold switch arm 28 which serves as an armature, in its attracted position, where it engages contact 29. The energization of solenoid 26 provided by thermocouple 25 is not enough, however, to cause switch arm 28 to be moved from its position of rest. If, for any reason, solenoid 26 becomes deenergized, switch arm 28 falls away from contact 29, and has to be reset manually before the circuit therethrough can be completed. If de-

sired, a sensitive safety switch of the type which picks up its armature automatically when the pilot is relighted, may be used.

A pressure responsive switch generally indicated at 30 cooperates with the thermostat 20 to control the energization of the valve 16. The switch 30 comprises a mercury switch 31 which is mounted on a pivoted support 32 against which a bellows element 33 bears. The bellows element is connected by means of a pipe 34 to the pipe 12 at the outlet side of the blower 13.

Power is supplied to the control system from lines 40 and 41 through a step down transformer 42 having a primary winding 43 and a secondary 44.

The thermocouple 25, which is of the concentric type, is provided with the usual members 45 and 46 of different thermoelectric characteristics which are jointed at 64 to provide the hot junction of the thermocouple. The inner member 45 is secured to a conductor 47 which is insulated as at 48. The outer member 46 is connected at 65 to a copper reducing sleeve 49 which in turn is connected to a copper tubing 51. The connection 65 between member 46 and sleeve 49 forms the cold junction of the thermocouple. The tubing 51 is electrically connected to one end of the solenoid 26, while the conductor 47 is connected to the other end.

The pilot 18 consists of a nozzle 50 which is mounted on the end of a pipe 51. This nozzle has an exterior opening 52 located centrally of its outer end and bounded by a flange 52a. Within the body of the nozzle is a partition 53 of a generally conical shape which is provided with a large central opening 54 and a plurality of small openings 55 spaced radially from the central opening. A second wall 56 is located at the back of the nozzle and serves to support substantially centrally thereof the thermocouple 25. The wall 56 is provided with suitable openings which permit the flow of gas therethrough. The conductors 47 and 51 pass along the center of the pipe 51 and out through a packing gland 58. Gas is supplied to the pilot burner 18 through the pipe 17 in which is inserted an air intake 59 of any suitable design. The pipe 17 is connected to the pipe 51 through a T connection 60. The pipe 51 is connected to one of the arms of the T connection and the gland 58 is connected to the other arm, while the pipe 17 is connected to the upright of the T. This construction enables the conductors 47 and 51 to pass out through the opening located centrally of the packing gland 58 without the tubing 51 touching the sides of the pipe 51 at any point. The conductors 47 are supported in the gland 58 by a fiber washer 61. In order to provide a pressure tight seal, metal washers 62 are provided in the packing gland, each of which has a slot extending from one edge thereof beyond the center. Two of these washers with their slots oppositely disposed are placed on each side of the fiber washer 61, as shown in Figure 3. The washers are clamped into the gland 58 by a packing nut 63.

As previously noted, an air intake 59 is provided so that a mixture of gas and air is supplied to the pilot burner 18. Because of this, combustion occurs immediately beyond the wall 53 which acts as a screen to prevent combustion on the upstream side of this wall. The outer portion of the nozzle 50 thus acts as a housing to confine the flame. This confining action is aided by the flange 52a. The result of this is

that the pilot flame, despite the turbulent conditions surrounding it, remains in igniting relation to the main burner. Furthermore, the confining action of the housing 50 results in the flame being more effectively directed against the hot junction 64 of the thermocouple. Thus, it is possible to use a fuel mixture of gas and air in the pilot burner in association with a forced draft gas burner and still obtain proper heating of the hot junction of the thermocouple.

The thermocouple 25 may be mounted so as to extend slightly eccentrically from the mouth 52 of the nozzle 50, if the nozzle 50 is of such a construction that it provides a symmetrical flow of gas through the opening thereof. It has been found that in such cases, if the thermocouple 25 is located in the exact center of the nozzle, a cone of unburned gas may form around the end of the thermocouple, and prevent it from receiving the full benefit of the heat of the pilot flame. When the pilot burner is mounted vertically, the thermocouple should be introduced eccentrically, but when the burner is mounted horizontally, the eccentric mounting is not important.

Operation

The various elements are shown in the positions they have when there is no demand for operation of the burner by the thermostatic device 20. It is presumed that the pilot 18 is lit and that the safety switch 27 has not opened. When the temperature of the room or space to be controlled falls below the value which the thermostat 20 is set to maintain, the switch arm 22 will be moved into engagement with the contact 23 thereby completing a circuit which will result in energization of the motor of the blower 13. This circuit may be traced from the upper terminal of secondary winding 44, as it appears in the drawing, through a conductor 70, contact 23, switch arm 22, bimetallic element 21, a conductor 71, contact 29, switch arm 28, conductors 72 and 73, a starting relay 74 for the motor of blower 13, conductors 75 and 76 to the lower terminal of secondary winding 44. Energization of the relay 74 will result in the connection of the blower motor to the line wires 40 and 41.

As soon as the blower has started the pressure in the outlet pipe 12 thereof will increase. The increased pressure will be carried through the pipe 34 to the bellows element 33. The expansion of this bellows will lift the support 32 so as to move the mercury switch 31 to close its contacts, which will result in the completion of an energizing circuit for the valve 16. This circuit may be traced from the upper terminal of secondary winding 44 through conductor 70, contact 23, switch arm 22, bimetallic element 21, conductor 71, contact 29, switch arm 28, conductor 72, a conductor 77, switch 31, conductor 78, valve 16, and conductor 76 back to the lower terminal of secondary winding 44. This will result in the opening of the valve 16 to supply fuel to the blower and mixer 13. A combustible mixture of fuel and air will then be blown from the mixer out through the nozzle of burner 11 and ignited by the pilot. The resulting combustion in the furnace 10 will raise the temperature of the room or space under control, and, as soon as it has reached the desired value, the thermostat 20 will operate to separate the contacts 22 and 23, thereby deenergizing the system. It should be noted that, because of the

pressure-responsive switch 30, fuel is not supplied to the burner until after a flow of air therethrough has been started. This scavenges the furnace of any accumulated gas, and also serves to prevent flash-back.

If the flame at the pilot burner should become extinguished at any time, the flow of gas through the nozzle thereof will operate to cool the hot junction of thermocouple 25 which has been in the pilot flame. As the temperature of the hot junctions falls, the electromotive force produced by the thermocouple soon becomes insufficient to maintain the energization of solenoid 26 with the result that switch arm 28 moves away from contact 29, and the system cannot then operate until the switch 27 is manually reset. It will be seen that by placing the thermocouple in the center of the pilot burner nozzle advantage is taken of the flow of gas through this nozzle to cool the cold junction of the thermocouple under normal conditions and to cool both junctions upon failure of the pilot flame. By reason of this construction the thermocouple is made much more sensitive to failure of the flame than any of the previously existing devices, and a more rapid response of the switch 27 to failure of the pilot flame is obtained.

It will be further apparent that the thermocouple lead 51 is protected by the pipe 51 from the heat of the burner. Furthermore, the flow of the gas and air mixture around the lead 51 keeps it well below the temperature (approximately 600 degrees F.) at which copper starts to oxidize.

While I have shown a specific embodiment of my invention for the purpose of illustration it is to be understood that my invention is limited only by the appended claims.

I claim as my invention:

1. A safety pilot for a fluid fuel burner control system, comprising a pilot burner having a plurality of apertures in the tip thereof, one of which is located centrally of said tip, and a thermocouple mounted so as to extend asymmetrically through said central aperture, with one junction on the outer side of said aperture and exposed to a flame resulting from fuel issuing through another of said apertures, and the other junction exposed to the unignited fuel flowing to said burner.

2. A safety pilot for a fluid fuel burner control system, comprising a pilot burner having a substantially cylindrical body, a supply pipe for said burner, one end of said body engaging said pipe, said body having a transverse wall near said one end, and a substantially conical wall intermediate its ends, said conical wall being coaxial with said cylindrical body, the other end of said cylinder being substantially open, each said wall having a plurality of apertures therethrough, one of said apertures being located substantially centrally of each said wall, and a thermocouple mounted in the central aperture of said transverse wall, and extending through the central aperture of said conical wall, with its hot junction exposed to the pilot burner flame, and its cold junction exposed to the fuel flowing from the supply pipe to the burner.

3. A safety pilot for a fluid fuel burner control system, comprising a pilot burner having a substantially cylindrical body and a substantially conical wall intermediate the ends of said

body and coaxial therewith, said wall having a plurality of apertures therethrough, a supply pipe for said burner, one end of said body being attached to said pipe and the other end being substantially open, and a thermocouple mounted through one of said apertures, with its hot junction extending through the open end of said body into the region of the pilot flame, and its cold junction exposed to the fuel flowing through the supply pipe.

4. In combination, a pilot burner having a substantially cylindrical body and a substantially conical wall intermediate the ends of said body and coaxial therewith, said wall having a plurality of apertures therethrough, a supply pipe for said burner, one end of said body being attached to said pipe and the other end having an inturned edge portion forming a single relatively large aperture therein, and a thermocouple mounted so as to extend through one of the apertures in said conical wall and the large aperture in said other end of said body with its hot junction in the region of the pilot flame, and its cold junction exposed to the fuel flowing through the supply pipe.

5. In combination, a pilot burner comprising a tubular body having an apertured partition therein, means for supplying a fuel mixture of gas and air to said tubular body so that when ignited a flame projects from said tubular body starting from said apertured partition, a thermocouple mounted so as to extend through said partition with one junction within said flame and the other junction within said tubular body in the direct path of the unignited fuel flowing through said body, and means projecting from said tubular body beyond said apertured partition and partially confining the flame so as to direct it against said one junction.

6. In combination, a pilot burner comprising a tubular body having an apertured partition therein, means for supplying a fuel mixture of gas and air to said tubular body so that when ignited a flame projects from said tubular body starting from said apertured partition, a thermocouple mounted so as to extend through said partition with one junction within said flame and the other junction within said tubular body in the direct path of the unignited fuel flowing through said body, and an open ended housing projecting from said tubular body beyond said apertured partition so as to confine the flame and direct it against said one junction.

7. In combination, a pilot burner comprising a tubular body having an apertured partition therein, means for supplying a fuel mixture of gas and air to said tubular body so that when ignited a flame projects from said tubular body starting from said apertured partition, a thermocouple mounted so as to extend through said partition with one junction within said flame and the other junction within said tubular body in the direct path of the unignited fuel flowing through said body, and a housing projecting from said tubular body beyond said apertured partition so as to confine the flame and direct it against said one junction, said housing terminating at its outer end in an opening surrounded by an inwardly extending flange which aids in confining said flame.
